CLAIM

The ornamental design for a reconfigurable insect toy, substantially as shown and described.

DESCRIPTION

FIG. 1 is a front side perspective view of a reconfigurable insect toy showing my new design in a beetle configuration;

FIG. 2 is a front elevational view;

FIG. 3 is a rear elevational view;

FIG. 4 is a top plan view;

FIG. 5 is a bottom plan view;

FIG. 6 is a right elevational side view which is a mirror image of the left elevational side view;

FIG. 7 is a front side perspective view of the invention reconfigured in the form of a humanoid robot;

FIG. 8 is a front elevational view of the embodiment of FIG. 7;

FIG. 9 is a rear elevational view of the embodiment of FIG. 7;

FIG. 10 is a top plan view of the embodiment of FIG. 7;

FIG. 11 is a bottom plan view of the embodiment of FIG. 7; and

FIG. 12 is a right elevational side view which is a mirror image of the left elevational side view of the embodiment of the FIG. 7.
